WINDSHIELD CLEANING SYSTEM

Erwin C. Horton, Hamburg, N. Y., assignor to
Trico Products Corporation, Buffalo, N. Y.

Application June 3, 1937, Serial No. 146,221

5 Claims. (Cl. 15—255)

This invention relates to automotive accessories such as automatic cleaners of the type usually employed in cleaning the windshields of motor vehicles.

5 In my present invention, I provide an accessory, such as a windshield cleaner mechanism which derives its actuating energy from a moving fluid stream, specified herein as the lubricating oil in the crank case of an internal combustion engine 10 but which might be any other available source of energy in the nature of a fluid stream moving under pressure.

An object of the present invention is the provision of a device of the class described wherein 15 the transmission of energy from the moving stream of oil to the windshield cleaner is positive and direct and for the attainment of that and other objects I have provided motor means actuated by the pressure or motion of the lubricant and mechanical drive means extending between the motor means and the accessory.

The motor means which I contemplate is so constructed and arranged that when the load imposed upon it exceeds its potential torque its 25 operation automatically ceases and the actuating fluid is merely by-passed about the movable part or parts of the motor without strain on the working parts or other injurious result.

The invention further has for its object to 30 provide an improved accessory system operated by a fluid circuit of the motor vehicle, wherein the arrest of the accessory is accomplished in a most satisfactory manner.

Cessation of operation of the accessory may 35 be accomplished mechanically as by arresting movement of the accessory or its mechanical drive means. I preferably so arrange my locking or stop means that it will always become effective to stop the mechanical drive means with the 40 cleaner or other accessory in a predetermined phase of its movement, regardless of the position of the accessory and the drive means at the moment the stop means is actuated to arrest further action thereof.

45 By my present invention I provide a device wherein the drive means from the source of energy to the accessory is wholly mechanical and positive and which may yet be acted upon at any convenient point on the accessory or through- 50 out the extent of the drive means to bring about cessation of operation with and disconnection or declutching of the drive means or the accessory. This makes for simplicity of construction and is accompanied by the advantage which de- 55 rives from the fact that neither the motor nor

the drive means are moving idly when the accessory is not in use.

In the drawing:

Fig. 1 illustrates a side elevational view of my new apparatus associated with a motor vehicle; 5

Fig. 2 is a diagrammatic front elevational view of the cleaner portion of my invention;

Fig. 3 is a cross-sectional view taken approximately on the line 3—3 of Fig. 1 and illustrating the mechanical power take-off means associated 10 with the fluid stream;

Fig. 4 is a view taken approximately from the position indicated by the line 4—4 of Fig. 1 and illustrating the means for arresting the operation of the automatic cleaner. In this view the 15 parts are in a position wherein the cleaner is operative;

Fig. 5 is a view similar to Fig. 4 but with the parts in position wherein operation of the cleaner is arrested; and 20

Fig. 6 is a cross-sectional view taken on the line 6—6 of Fig. 4.

In the illustrated embodiment the numerals 10 and 11 in Fig. 1 designate the hood and cowl portions, respectively, of a motor vehicle and the 25 windshield thereof is indicated at 12. The internal combustion driving engine 13 of the vehicle has a lubricant circulating pump 14 disposed in its crank case 15.

The drive for the accessory is depicted herein 30 as being operated from the lubricating system of which the pump 14 constitutes a part. Accordingly, an opening is provided in the wall of the crank case 15 for receiving and positioning the means for taking off power for operating 35 the windshield cleaner, which power take-off means includes the closure member 16 adapted to be secured over the opening and providing journalled support for a shaft 17 carrying a toothed or bladed wheel such as the turbine 40 wheel or rotor 18 disposed in the interior of the crank case for being acted upon by the flowing liquid. A portion of the lubricating fluid is directed through a conduit 25 and, acting under the pressure imparted thereto by the circulating 45 pump 14, is discharged through a jet 18 provided at the terminal portion of the conduit 25. The jet 19 is supported against the interior of the crank case 15 in such position that the stream of fluid emerging therefrom impinges against the 50 blades or impellers of the rotor 18 causing rotation thereof.

The power developed is transmitted to the accessory, herein the wiper 38, by a positive or mechanical transmission. The transmission 11- 55

lustrated includes a worm or helical pinion 20 on the outer end of the shaft 17 for engagement with a worm wheel or helical gear 21 having its axis substantially at right angles to the worm or pinion 20 and positioned upon the terminal portion of a flexible shaft 22 leading up to the accessory. The gear drive just described is enclosed in an extension 23 provided on the plate member 16 and has a suitable cover 24. The flexible shaft 22 is provided with a suitable confining casing 22a or conduit in a manner which is well known.

Referring to Fig. 2, the accessory is shown as comprising a pair of wiping arms 30 pivotally mounted at 31 on the opposite sides of the outer surface of the windshield 12 for moving the carried wipers 38 in wiping contact therewith. Their pivot shafts are provided with pinions 32 meshing with adjacently mounted gears 33 which carry therewith crank arms 34. Disposed between the two wiper mountings is a rotatable shaft 35 carrying a crank arm 36 which is preferably shorter than the crank arms 34 and connected to both crank arms 34 by links 37.

It will be seen that, owing to the fact that the crank arms 34 are substantially longer than the crank arm 36, continuous rotation of the central shaft 35 and its associated crank arm 36 will, through the medium of the links 37 and the crank arms 34, cause the gears 33 and consequently the pinions 32 and the wiper arms 30 to oscillate about their pivot points 31. Oscillation of the arms 30 causes the wiping blades 38 to move back and forth across the surface of the windshield 12 for cleaning the same. A gear 40 is fixed to the central shaft 35 and meshes with a worm 41 carried by the end of the flexible shaft 22 opposite the end carrying the gear 21 so that rotary motion of the rotor 18 is transmitted to the shaft 35.

For parking or arresting the wipers at a definite point, outside the field of vision, the central shaft 35 and the end of the flexible shaft 22 carrying the worm 41 are both journalled in a casing 42 which is supported against a bracket member 43 by studs or pins 44 which permit horizontal sliding movement of the casing 42.

Referring to Fig. 4, the lower left hand stud 44 is carried by the casing 42 and its cooperating horizontal slot is formed in the bracket 43. The remaining two studs 44 are carried by the bracket 43 and their cooperating horizontal slots are formed in the casing 42. It will therefore be seen that horizontal movement of the casing 42 from the position shown in Fig. 4 to the position shown in Fig. 5 is accompanied by similar horizontal movement of the lower left hand stud 44 but that the remaining two studs 44 will remain relatively stationary. An elongated slot 52 is formed in the bracket member 43 to permit horizontal movement of the shaft 35 with respect thereto.

For controlling the horizontal movement of the casing 42 an arm 45 is positioned against the face of the bracket member 43 opposite the casing 42 and supported thereagainst by an eccentric pivot 46. The eccentric pivot 46 is carried at one end of a flexible shaft 47 whose other end is journalled in a convenient location for manipulation by the operator of the vehicle, in the present instance the instrument board of the vehicle, and is provided with a knob 48 to facilitate manual rotation thereof.

The outer end of the arm 45 is pivotally connected to one of the casing supporting studs or

pins 44 and consequently manual rotation of the knob 48 in either direction will, because of the eccentric mounting of the arm 45, cause the casing 42 to move horizontally between the terminal positions illustrated in Figs. 4 and 5.

When the casing and its associated parts are in the position illustrated in Fig. 4 the crank arm 36, which is fixed to the shaft 35 and spaced from the bracket 43 sufficiently to clear the arm 45, rotates freely and oscillates its associated arms 33 to cause normal operation of the cleaner. When, however, the knob 48 is rotated to move the eccentric 46 and the arm 45 into the position illustrated in Fig. 5, the casing is moved with respect to the bracket 43 into such position that a pin 50 carried by the bracket 43, lies in the path of rotation of the arm 36, preventing further rotation thereof and stopping the arm 36 in a predetermined angular position.

In normal operation the rotation of the crank 36 results in oscillation of the wiper arms 30 and their associated blades 38 through an arc which is defined in Fig. 2 by the diagrammatically illustrated blade and arm A and the dot and dash line B. The pin 50 is so located on the bracket 43 that rotation of the crank 36 is arrested in a position wherein the links 37, the arms 34, the gears and pinions 33 and 31, and the wiper arms 30 are at one end of their oscillatory path of movement. In the present instance that end is attained by arresting the crank 36 in an approximately horizontal position.

It will be noted that the arresting movement of the assembly, which includes the casing 42, arm 36, its shaft 35, the gear 40 and the worm 41, is from right to left as viewed in Fig. 4 and that this longitudinal movement of the parts mentioned results in additional oscillation of the arms 34, the gears and pinions 33 and 31, and the wiper arm 30, causing the wiper arms 30 and their associated blades 38 to come to rest in the position indicated by the dot and dash line C. In this way the wipers are always stopped or parked in a position outside their normal field of operation and outside the normal field of vision of the operator of the vehicle.

The wiper element 38 will be oscillated over the glass as long as the cleaner system is in operation and the operating flow of liquid continues in circulation. However, to arrest the wiper action it is only necessary to stop the mechanical driving parts between the wiper and the liquid flow since provision is made to by-pass the liquid without discontinuing its circulatory movement. This may be accomplished by a separate channel although it is desirably performed by having enclosing housing 15 so dimensioned as to afford the desired clearance about the driving member of the fluid pressure operated motor element 18.

While one form of my present invention has been specifically illustrated and described, it is to be understood that various modifications and changes may be made without departing from the spirit or scope of the invention as defined in the appended claims.

What is claimed is:

1. A motor vehicle having a power plant with a force feed lubricating system, a fluid pressure actuated motor embodying a fluid driven rotating element mounted in a branch path of flow of the lubricant from the system to be driven thereby, a remotely located accessory shaft mechanically connected to the rotating element by flexible

- drive means for being driven thereby, and means for positively arresting the accessory shaft against the tendency to move caused by the fluid flow.
5. A motor vehicle having a power plant with a force feed lubricating system, a fluid pressure actuated motor embodying a fluid driven rotating element mounted in a path of flow of the lubricant from the system to be driven thereby and so constructed that also it may be held arrested when said fluid pressure is acting thereon, a remotely located accessory shaft mechanically connected to the rotating element by mechanical transmission means for being driven thereby, and means for positively arresting the accessory shaft against a tendency to move caused by the fluid flow.
3. A motor vehicle having a power plant with a force feed lubricating system operated by said power plant, a fluid pressure actuated motor comprising a fluid driven element mounted in the path of flow of the lubricant from the system to be driven thereby and so constructed that also it may be held arrested when said fluid pressure is acting thereon, a remotely located accessory shaft mechanically connected to the fluid driven element by mechanical means for being driven thereby, said force feed lubricating system and fluid pressure actuated motor constituting a fluid slip clutch between the power plant and said accessory shaft whereby the driving relationship of the power plant to the accessory shaft may be disrupted by arresting the accessory shaft, and means for positively arresting the accessory shaft at a predetermined point in its cycle of operation.
4. A motor vehicle having an internal combustion propelling engine and a crank case therefor, a force feed lubricating system associated with said crank case, said crank case having an opening in the wall thereof, a removable support adapted to fit over and close said opening, a drive shaft journaled in said support, a rotor secured to said shaft within said crank case and removable with said support, and an oil jet disposed adjacent thereto and adapted to discharge oil under pressure from the lubricating system against said rotor, a portion of said shaft extending outside of said support, a remotely located accessory, and flexible drive means positively connecting said shaft and said accessory for operating the latter.
5. A motor vehicle having an internal combustion propelling engine and a crank case therefor, a force feed lubricating system associated with said crank case and having a pressure jet disposed therein adjacent a wall of said crank case for emitting lubricating fluid under pressure, said crank case having an opening in the wall thereof adjacent said jet, a removable support adapted to close said opening and having a drive shaft journaled therein, a rotor secured to said shaft within said crank case to be driven by fluid discharging from said jet under pressure, said rotor being openly disposed in said crank case whereby spent operating fluid falls to the bottom of the crank case, and said rotor being withdrawable from operating relationship with the fluid jet with and upon removal of the support from said opening, a portion of said shaft extending outside of said support, a remotely located accessory, and flexible drive means positively connecting said shaft and said accessory for operating the latter.
